Patented Mar. 12, 1918.

UNITED STATES PATENT OFFICE.

ODOARDO A. TORRAZZA, OF PANAMA, PANAMA.

BOTTLE AND JAR CLOSURE.

1,259,168.

Specification of Letters Patent. Patented Mar. 12, 1918.

Application filed December 30, 1916. Serial No. 139,790.

To all whom it may concern:

Be it known that I, ODOARDO A. TORRAZZA, a citizen of the Republic of Switzerland, and a resident of the city of Panama, Republic of Panama, have invented certain Improvements in Bottle and Jar Closures, of which the following is a specification.

One object of my invention is to construct a bottle or jar stopper which will be firmly held to the bottle or jar, and which can be readily opened by shifting a lever carried by the stopper.

A further object of my invention is to so construct the gripping means of the stopper that a sealing wire can be applied.

The invention is primarily intended as a temporary stopper, but it can be used as a permanent stopper if desired.

In the accompanying drawing:—

20 Figure 1, is a side view, partly in section, illustrating my improved bottle stopper in the closed position;

Fig. 2, is an end view, partly in section, showing the stopper in the closed position;

25 Fig. 3, is an end view showing the lever raised so as to release the retaining hooks;

Fig. 4, is a view showing the lever raised and the hooks in the open position ready to be applied to the bottle;

30 Fig. 5, is a detached perspective view of the bottle stopper;

Fig. 6, is a detached perspective view of the locking lever;

Fig. 7, is a detached perspective view of 35 one of the retaining hooks; and

Fig. 8, is a perspective view showing the sealing wire applied to the stopper.

Referring to the drawing, 1 is the bottle, in the present instance having a mouth 2 40 and an annular groove 3 on the exterior of the mouth end. 4 is the casing of my improved bottle stopper made of sheet metal and having a flange 5 which extends over the edge of the bottle and centers the stopper in respect to the bottle. Located within

45 in the stopper is a washer 6, preferably of cork, which rests against the end of the bottle, as shown in Figs. 1 and 2, so that, when the stopper is locked to the bottle, the joint 50 is air and fluid tight. Projecting from the opposite sides of the stopper 4 are ears 7. 8, 8 are retaining hooks mounted on pivot pins 9 carried by the ears, as clearly shown in Fig. 1. The hooks 8 are made of metal 55 bent into shape, as clearly shown in Fig. 7, having a coiled engaging portion 10, which

is so shaped as to enter the groove 3 at the mouth of the bottle, and also has a flat bearing portion 11 for the ball ends of the locking lever.

60 12 is a locking lever consisting of a body portion 13, which extends through a transverse opening in the metallic portion of the bottle stopper, as shown in Fig. 1, and curved portions 14, which rest in grooves 15 in the hooks 8 when in the closed position, as in Figs. 1 and 2. At the end of this curved portion are balls 16, which rest against the flat bearing portions 11 of the retaining hooks. When the lever is moved 70 to the position illustrated in Figs. 1 and 2, the retaining hooks are forced into the recess 3 of the bottle, causing the stopper to be pressed tightly on the end of the bottle and making a tight joint between the washer 75 6 and the mouth end of the bottle.

When it is desired to open the bottle, all that is necessary is to turn the lever 12 from the position illustrated in Fig. 2 to that illustrated in Fig. 3, when the retaining 80 hooks are released and the stopper can be quickly detached from the bottle. When the stopper is to be applied to a bottle, all that is necessary is to mount it in position and to swing the lever from the position 85 illustrated in Fig. 3 to that illustrated in Fig. 2.

It will be noticed that the locking hooks are perforated at 17 so that a wire 18, Fig. 8, can be passed around the neck of the bottle and through the perforations. The wire can be twisted and a seal applied, as at 19, so as to prevent any one tampering with the contents of the bottle. By merely cutting the wire and shifting the lever, the stopper 95 can be opened and can be used again to close the bottle, since the stopper is not destroyed, or its efficiency in any way lessened when detached.

My improved stopper can be inexpensively 100 made and can be ornamented so as to present an attractive appearance. If desired, it can be made out of silver, or other material, so as to correspond with the finish of a more expensive receptacle of cut or etched 105 glass, it being especially applicable to close bottles such as are used in traveling bags, because the contents will not leak or run out when my improved closure is used.

I claim:—

1. The combination of a bottle having an annular groove near its mouth end; a stop-

per adapted to close the mouth of the bottle and having two rigid retaining hooks pivotally mounted thereon and arranged to enter the groove of the bottle; means for rigidly holding the hooks in the closed position; and means journaled in the stopper and arranged to swing with respect thereto to release or engage the hooks.

2. The combination in a bottle stopper, 10 of a body portion adapted to fit over the end of a bottle; two retaining hooks pivoted to the body portion of the stopper at each side thereof and arranged to engage the bottle; and an independent locking lever journaled in the body portion of the stopper and arranged to hold the hooks in engagement with the bottle.

3. The combination of a bottle having an annular groove directly below the mouth 20 thereof; a bottle stopper having a flanged body adapted to fit over the mouth of the bottle and having ears at each side; two retaining hooks pivoted to the ears and shaped to extend into the groove of the 25 bottle and having bearing portions; and a pivoted locking lever mounted on the body

portion and adapted to be turned so as to rest against the bearing portions of the hooks, retaining them in the locked position.

4. The combination in a bottle stopper, of 30 a body portion having a flange; a sealing disk closing the mouth of a bottle; two retaining hooks having curved portions arranged to enter a groove in the bottle and each having a grooved portion 35 and a flat bearing surface; and a locking lever pivotally mounted in the body portion and curved at each end and adapted to enter the grooves in the retaining hooks and having enlargements at the end arranged 40 to bear against the flat surfaces of the said hooks to hold them in the locked position.

5. The combination in a bottle stopper, of 45 a body portion adapted to fit over the ends of a bottle; two retaining hooks pivoted to the body portion of the stopper at each side thereof; and a locking lever pivotally mounted in the body portion, said locking lever being bent and having a ball at each end adapted to press against the hooks and 50 to force them in contact with the bottle.

ODOARDO A. TORRAZZA.
